UNITED STATES PATENT OFFICE.

ALBERT HARRISON ROLLIN, OF COLDWATER, MICHIGAN.

RATCHET-WRENCH.

SPECIFICATION forming part of Letters Patent No. 324,169, dated August 11, 1885.

Application filed March 20, 1885. (No model.)

To all whom it may concern:

Be it known that I, ALBERT HARRISON ROLLIN, of Coldwater, in the county of Branch and State of Michigan, have invented a new and useful Improvement in Ratchet - Wrenches, of which the following is a full, clear, and exact description.

The object of my invention is to provide a ratchet-wrench which can be quickly adjusted and will securely hold different sizes of nuts, bolts, &c., and which can be readily released after the nut or bolt has been driven home.

My invention consists of a ratchet-head having a series of cams which coincide with and work movable jaws, peculiarly constructed pawls which engage with teeth on the cam-head, a spring for releasing these pawls, an oscillating handle provided with operating-pawls, and a collar adapted to throw out of engagement either or both of the operating-pawls.

My invention further consists in the details of construction and combinations of parts, as will be hereinafter fully described and claimed.

25 Reference is to be had to the accompanying drawings, forming a part of this specification, in which similar letters of reference indicate corresponding parts in all the figures.

Figure 1 is a front elevation of my improved wrench. Fig. 2 is a back elevation of the same. Fig. 3 is a longitudinal section on the line $x x$, Fig. 2. Fig. 4 is a detail view of one of the pawls for operating the movable jaws. Fig. 5 is a sectional view on the line $y y$ of Fig. 3. Fig. 6 is a sectional view on the line $z z$ of Fig. 3. Fig. 7 is a side view of the ratchet-head. Fig. 8 is a sectional view on the line $z' z'$ of Fig. 2.

In the drawings, A represents the ratchet-head, having teeth *a* on its periphery, into which the pawls *b* and *b'* engage.

B B' are semicircular plates connecting the handle with the ratchet-head from the offset g. These plates are flattened to form a recess to receive the ratchet-head A. On the inner sides of said flattened portions are formed lugs C, which project in a plane at right angles to the said plates. These lugs C are adapted to work in circular grooves c in the head A. Screws d secure the plates B B' together after the lugs C have been inserted into the grooves c. By this arrangement the head A is securely con-

nected with the handle, and at the same time allows the handle to freely move to the right or left around the head. The pawls *b* and *b'* which engage the teeth *a* work in openings in the plates *B* and *B'* and are pivoted at *e*. 55

D is a contractile spring for holding the pawls b and b' in contact with the teeth a. The plates B and B' are screw-threaded internally at their outer ends to receive an externally-threaded nut, E, through which the shank of the handle F passes. Before screwing the nut E on a loose collar, G, is passed on the semicircular plates B and B', which collar works between offsets g on the plates B and B' and the nut E. 60 65

On the internal surface of the collar G, and at the outer part thereof, it has a recessed or reduced portion, G', which extends about three-quarters around. This recess G' is for the reception of the lower angular projections, b^2 , of the pawls b and b', when they are in engagement with the teeth a on the head A. When it is desired to throw one of the pawls out of engagement with the teeth a, the collar G is given a slight turn either to the right or left, which forces one of the projections, b^2 , out of the recess G' onto the unbroken surface of the collar G, which will throw the corresponding pawl out of engagement. By turning the collar G so as to allow both pawls to fall into the recess G', the operation of what is termed "coaxing a nut" can be performed—that is, to work it back and forth for a portion of a turn before going ahead.

On the head A, and facing inwardly, a series of cams, H, are formed, upon which the movable jaws I work. Each jaw I is provided on its inner face with the shoulder I' and the lug I², and on its outer surface at its opposite end with the lug I³.

In a groove, i , which extends half-way around the head, as shown in Figs. 5 and 7, a semicircular holder, J , is adapted to move, and pivoted to this holder at l are two radial bars, j , which extend through slots i' in the head A , and into slots m in the movable jaws I . By these means the jaws I are held in their proper relative positions opposite each other. The movable jaws I are also held in place by means of short projecting lugs k on their ends, Fig. 6, which have eyes for the reception of retaining-pins p . The lugs k are passed through

slots *o* in the walls of the cams *H*, and the pins *p* inserted into the eyes, thereby holding the jaws in place and at the same time allowing them play to the full extent of the slots *o*.
 5 On the inner face of the head *A*, and just above the slots *o*, teeth *K* are formed, Fig. 2, with which engage the pawls *L*, attached to and through the medium of which the movable jaws are tightened on the nut, bolt, &c.
 10 Springs *q* are secured in depressions in the face of the jaws *I* and bear against the pawls *L* to prevent their dropping out of contact with the teeth *K*. The pawls *L* have shallow slots *M* on their engaging-points, through which 15 the spring *N* passes, as shown by Fig. 4. The spring *N*, which may be made of any suitable spring-metal wire, passes around the face of the head *A*, and is held in proper working position to the pawls *L* by means of hooks *r*, 20 which are secured in the head *A*, and under which the spring *N* passes. The ends of the said spring are carried from the head down through the semicircular plates *B* and *B'* to a small opening in the head of a screw-plug, *O*, and there secured. This plug *O* screws into 25 the shank of the handle *F*.

In operating the wrench the jaws *I* are placed over a nut. Either of the pawls *b* and *b'* are brought by means of the collar *G* into engagement with teeth *a*. The handle is moved from right to left, or vice versa. This movement brings the pawls *L* into play, which causes the jaws *I* to grip the nut tightly by the action of the cams *H*, and then the head 35 *A* revolves and the nut is driven home.

In order to release the wrench from the nut, the handle is drawn outward in the nut *E*. This causes the spring *N* to contract laterally, and as the pawls *L* straddle the spring it is 40 evident that the pawls *L* will be thrown out of engagement with the teeth *K*, and the jaws *I* will then become loose and can be released from the nut, &c.

S represents a wedge-shaped releaser, which 45 is held in position by means of a pivot, *s*, projecting from the plate *B'*, and which works between said plate and the head *A*. The pivot *s* projects through a slot, *s*, in the releaser *S*, and in this slot under the pivot *s* a spiral spring, *t*, is seated.

When the spring *N* is contracted, as above described, it will force the releaser *S* out toward the head *A*, and when the pressure of the spring *N* is removed the spiral spring *t* 55 will return the releaser *S* to its first position. The object of this is as follows: If after screwing up a nut it is found that either of the pawls *L* come to a rest just above the releaser *S*, where the spring *N* cannot act against it, 60 the releaser *S*, moving up, will accomplish the object of throwing the pawl out of engagement.

Having thus described my invention, I claim as new and desire to secure by Letters Patent—
 65 1. In a wrench, the combination, with the head *A*, having grooves *c*, of the plates *B* and *B'*, carrying handle *F*, and having lugs *C*,

which work in the grooves *c*, the said plates *B* *B'* being secured together by screws *d*, substantially as and for the purpose specified. 70

2. In a wrench, the combination, with the head *A*, having teeth *a*, of the pawls *b* and *b'*, having angular projections *b*², and working through slots in the semicircular plates *B* and *B'*, and pivoted at *e*, said pawls being thrown 75 into and out of engagement by means of a spring, *D*, and collar *G*, having reduced portion *G'*, substantially as and for the purpose specified.

3. In a wrench, the head *A*, having teeth *a*, 80 in combination with the pawls *b* and *b'* and the collar *G*, having recessed portion *G'* to receive the angular projections *b*² on the pawls *b* and *b'*, substantially as and for the purpose specified. 85

4. In a wrench, the combination, with the head *A*, having a series of cams, *H*, of the jaws *I*, each provided with a shoulder, *I'*, and lugs *I*' *I*', substantially as herein shown and described. 90

5. In a wrench, the combination, with the head *A*, cams *H*, and jaws *I*, of the semicircular holder *J* sliding in the groove *i*, and having short bars *j*, passing through slots *i*' and into slots *m* in the jaws *I*, substantially 95 as and for the purpose specified.

6. In a wrench, the combination, with the head *A*, cams *H*, and jaws *I*, of the lugs *k* projecting through slots *o*, and having eyes to receive pins *p*, substantially as and for the purpose specified. 100

7. In a wrench, the head *A*, having a groove, *i*, and slots *i*' to receive the semicircular holder *J* and radial bars *j*, in combination with the jaws *I*, having lugs *k*, projecting 105 through slots *o*, and pins *p*, inserted into eyes in the lugs *k*, substantially as and for the purpose specified.

8. In a wrench, the combination, with the jaws *I*, resting against cams *H*, and adapted 110 to be held in position by means of semicircular holder *J*, having radial bars *j*, and held to the cams *H* by lugs *k* and pins *p*, of the pawls *L*, having contact-springs *q*, said pawls engaging the teeth *K* in the head *A*, substantially 115 as and for the purpose specified.

9. In a wrench, the combination, with the pawls *L*, of the spring *N*, held to head *A* by hooks *r*, and passing through open slots *M* in the pawls *L*, the said spring being fastened 120 to handle *F* by means of screw-plug *O*, substantially as and for the purpose specified.

10. In a wrench, the combination, with the pawls *L*, spring *N*, and movable handle *F*, of the wedge-shaped releaser *S* between plate *B'* 125 and head *A*, and having slot *s* to receive a pivot projection, *s*', and a spring, *t*, the releaser *S* being operated by means of spring *N*, substantially as and for the purpose specified.
